In Germany December 12, 1931

6 Claims. (Cl. 176—124)

The invention relates to a method of controlling discharge tubes of the positive column type for television purposes.

The main object of the invention is to control discharge tubes filled with sodium vapor and having a positive luminous column by adjusting the operating temperature of the tube in such manner that the light density of the luminous column is substantially a linear function of the grid voltage of the thermionic valve which controls the discharge tube and normally forms the output valve of the receiver amplifier.

In order to receive an undistorted reproduction of television transmission it is essential, that not only all parts of the transmission system operate faultlessly, but also that the intensity of the controlled source of light at the receiver varies in proportion to the fluctuations of the grid potential of the output tube of the receiver amplifier.

Assuming, that the controlled source of light is arranged in the anode circuit of this output tube, which is the most simplified arrangement, then the above condition is fulfilled provided a linear function exists on one hand between the grid potential and the anode current, and on the other hand between the anode current and the intensity of light. For the purpose of obtaining proportionality between the fluctuations of the grid potential and the fluctuations of the anode current it is necessary that the working characteristic be a straight line, which in turn occurs only when—while operating in the straight region of the static characteristic of the tube—the A. C. resistance of the anode circuit (in this case substantially the controlled source of light) is constant.

While it was not difficult to fulfill these conditions when employing the well known sources of light such as glow lamps and kino lamps, it was at first extremely difficult to operate discharge tubes of the positive-column type, for example the new Na-surface lamps, which only very recently have been employed for television purposes.

It is now an important object of the present invention to overcome these difficulties encountered in the control of discharge tubes filled with sodium vapor. Experiments have shown that the A. C. resistance of these sodium filled lamps is not constant, and furthermore that there is no linear function between their intensity of light and the strength of their operating current. According to the invention, however, these difficulties may be largely overcome by operating the lamp at a predetermined and properly adjusted operating temperature. In the following the in-

vention is described by way of example based on experiments made with Na-surface lamp. The same considerations, however, apply also to other discharge tubes having a positive column and a heated cathode.

As well known, the Na-surface lamp is operated with an additional exterior heating means. Other discharge tubes, however, need only be provided with some heat protecting means to prevent excessive loss of heat and to enable the tube to create its own operating temperature. In these last mentioned tubes the adjustment of the required operating temperature according to the invention may be obtained by suitably selecting an average operating current.

In the drawings:

Fig. 1 shows the static resistance characteristic of an Na-surface lamp at three different operating temperatures. It will be noted that all three characteristics are descending, only the one taken at 180° C., is approximately linear, so that in this case the A. C. resistance is practically constant within a certain range of current.

Fig. 2 shows the relationship between the intensity of light and the current intensity at the three operating temperatures recorded in Fig. 1 and it can be seen that only when in this particular lamp the operating temperature is 180° C., the light intensity is a linear function of the current intensity, whereas the same deviates very appreciably from the desired proportionality at temperatures which are only 30° above or below this value.

Fig. 3 shows the relationship between the light intensity and the operating temperature at three different currents. It can be seen that at an operating temperature of 180° C. (which has been found to be most favorable) the maximum current amplitudes of approximately 100-140 milliampere (at an average supply current of approximately 50-70 milli-ampere), produce approximately the maximum intensity of light which the lamp may create at its best. According to the invention, the discharge tubes are maintained during their operation at a temperature at which (1) the light intensity varies in proportion to the current intensity, (2) the A. C. resistance is approximately constant, and (3) approximately the maximum light intensity is obtained. Obviously, the condition that the A. C. resistance should be constant is also fulfilled when the same is zero; this means, however, that the potential at the lamp must be constant.

Fig. 4 shows that by superimposing a properly selected high frequency current over the operat-

ing D. C., the characteristic of the lamp may be changed in such manner, that the voltage at the lamp is constant over the greater part of the current range employed during the modulation—⁵ or in other words that the A. C. resistance is practically zero. The light intensity of the lamp remains practically unaffected by the superposed high frequency current.

Fig. 5 shows diagrammatically the circuit used with the discharge tube. In this figure 1 is the output valve of the receiver amplifier; 2 is the discharge tube with a positive luminous column and a heated cathode; 7 represents the anode circuit of the amplifier in which the discharge tube 2 is arranged; 5 is an adjustable resistance for controlling the current passing through the discharge tube, 6 is a condenser in shunt to said resistance 5; and 3 indicates a high frequency generator for capacity coupling of tube 2 to the high frequency circuit by means of a metallic plate 4. This high frequency generator is used for superposing a high frequency current over the operating D. C. as shown in Fig. 4. The discharge tube 2 is placed in a casing 9, preferably of heat insulating material. An electric heating resistance 10 may be employed to maintain the desired operating temperature for the tube 2 within the casing.

The maintenance of a constant A. C. resistance and of a linear function between the intensity of light and the strength of the operating current (characteristic of intensity of light) make possible a distortionless television reception. But it is also possible to prevent distortions in the reproduction of the television image by compensating for any variation of the A. C. resistance by a corresponding non-proportionality of the characteristic of the intensity of light, which in turn may be obtained by a suitable selection of the operating temperature. Obviously a further possibility of compensation consists in the displacement of the working point along the tube characteristic. The last two methods of compensation, however, are seldom used in general practice. When in the foregoing the A. C. resistance of the lamp has been mentioned, it should be understood that always the A. C. resistance was meant as it results from the statically recorded characteristic of the lamp. The A. C. resistance, however, may also depend upon the frequency or upon that condition of operation of the lamp which prevailed at the immediately preceding instant. This, however, does not result in any appreciable variation in the working diagram of the lamp, which for the sake of simplicity has been considered to follow the static characteristics, since the principle is the same.

The above considerations and the diagrams shown in the Figs. 1-4, apply in the first place when the discharge tubes are operated with D. C. potential. The same considerations, however, may be applied correspondingly when the discharge tubes are operated exclusively with high frequency current. When the various transmission means in the system do not operate faultlessly, which is necessary for an undistorted television reception, then the distortions

which occur in any one of the transmission means may likewise be compensated by a suitable selection of the operating temperature of the discharge tube.

It is, of course, understood that the invention is not limited by the specific description set forth in the above, and that numerous modifications are quite possible within the scope of the appended claims.

What I claim as my invention is:

1. A method of controlling discharge tubes filled with sodium vapor and operating with positive column and heated cathode, consisting in so adjusting the operating temperature of the discharge tube that the intensity of light is a substantially linear function of the grid potential of the audion controlling the discharge tube.

2. A method of controlling discharge tubes filled with sodium vapor and operating with positive column and heated cathode, consisting in so adjusting the operating temperature of the discharge tube that the A. C. resistance is approximately constant, and that at the same time at this temperature the intensity of light is directly proportional to the current intensity.

3. A method of controlling discharge tubes filled with sodium vapor and operating with positive column and heated cathode, consisting in adjusting the operating temperature of the discharge tube so that the intensity of light is a substantially linear function of the grid potential of the audion controlling the discharge tube, and superposing a high frequency current over the D. C. for the purpose of acquiring constancy of the A. C. resistance.

4. A method of controlling discharge tubes filled with sodium vapor and operating with positive column and heated cathode, consisting in adjusting the operating temperature of the discharge tube so that the intensity of light is directly proportional to the current intensity, and superposing a high frequency current over the D. C. for the purpose of acquiring constancy of the A. C. resistance, substantially as described.

5. In a method for controlling a hot-cathode discharge tube filled with sodium vapor and having a positive luminous column, said discharge tube being arranged in the anode circuit of the output valve of an amplifier, the step of adjusting the operating temperature of the discharge tube in such manner that the light intensity of said positive luminous column is substantially a linear function of the grid voltage of said output valve.

6. In a method for controlling a hot-cathode discharge tube filled with sodium vapor and having a positive luminous column, said discharge tube being arranged in the anode circuit of the output valve of an amplifier, the step of adjusting the operating temperature of the discharge tube in such manner that the light intensity of said positive luminous column is substantially a linear function of the grid voltage of said output valve, whereby at this operating temperature the highest intensity of light is produced.

GEORG SCHUBERT.
